F. L. ELDRIDGE

SPARKING PLUG

Filed April 10, 1922

FIG.1.

UNITED STATES PATENT OFFICE.

FRANCIS LAYTON ELDREDGE, OF BOURNEMOUTH, ENGLAND.

SPARKING PLUG.

Application filed April 10, 1922. Serial No. 551,232.

To all whom it may concern:

Be it known that I, FRANCIS LAYTON ELDREDGE, a subject of the King of Great Britain, residing at Bournemouth, Hampshire, England, have invented an Improved Sparking Plug, of which the following is a specification.

This invention relates to ignition devices for internal combustion engines of the type having a plurality of pairs of sparking points, only one pair being operable at a time while all the other pairs are cut out of communication with the engine cylinder and out of the operating electrical circuit.

One object of the present invention is to provide an ignition device of the type referred to having as few parts as possible. Another object of the invention is to construct such a device that it may be fitted to existing sparking plug seatings or to the plug openings of engine cylinders. A further object is to provide a sparking plug in which as much as possible of the electrical connections are covered in, and another object is to facilitate fixing electrodes in such sparking plugs.

I will now describe several constructions, by way of example, embodying the present invention, with reference to the accompanying drawings, in which:—

Fig. 1 is a sectional elevation of one form of plug;

Fig. 2 is an underside plan view of the construction shown in Fig. 1;

Fig. 3 is a section on the line 3—3 of Fig. 1;

Fig. 4 is an outside elevation of a modified form;

Fig. 5 is an underside plan view of the form shown in Fig. 4;

Fig. 6 is a sectional elevation of the construction shown in Fig. 4;

Fig. 7 is a further underside view of the construction shown in Figs. 4, 5 or 6 showing an alternative position of the valve member;

Fig. 8 is a horizontal section on the line 8—8 of Fig. 6; and

Fig. 9 is a sectional elevation of a further modified form of the invention.

Each of these constructions are characterized by two main parts, viz, an insulating body formed with integral chambers, through each of which depend electrodes and an associated metal body provided with housings adapted to register with the chambers afore-

said and to accommodate the portions of the electrodes depending from the insulating body.

Referring to the drawings, the insulating body 11 provided with an annular flange 12 is centrally perforated to receive an axis spindle 21 for a valve 20 operated by a control cap 23. Symmetrically formed in the body and about the perforation is a series of chambers 13. With the insulating body is associated a metal body comprising a cup 14 adapted to receive the insulating body, and a solid stem 15 perforated axially in continuation with the central perforation in the body 11. Within the stem 15 is a series of separate housings 16 adapted to register with the chambers 13 aforesaid. In each of the chambers is rigidly held an electrode 17, which depends from the body 11 and into a housing in the solid stem 15. The bottom of each housing is constricted, as at 18, so as to furnish the sparking point or points to operate with the electrode disposed therein.

In the construction shown, a tubular nut 19 is provided and is adapted to screw into the cup 14 in order to engage against the flange 12 and hold the insulating body within the cup, but alternatively, the top of the cup may be swaged in over the bottom flange, although of course in such construction repairs could not be effected within the plug.

In order to provide means for shutting off all but one of the housings from an associated combustion space, the bottom face of the metal body is formed as a seating for the valve 20 mounted on the spindle 21, the valve having a single opening 22 dimensioned to register with the opening of a housing, while the rest of the valve covers the remaining housings. The position of the valve with regard to the housings is determined by rotating the control cap 23.

To accommodate the control cap 23, the top of the insulating body is formed with an annular ridge 24 at the top, on which bears a disc 25 formed on the spindle 21 and fitted to the cap 23, the cap thus being fixed to the valve spindle 21 and disposed for rotation on the said ridge. Within the ridge is arranged a spring 26 which is in compression when the cap is fitted, the spring therefore functioning as a means for holding the valve 20 hard against its seating in order to form substantially a gas-tight joint.

In order to obtain a gas-tight joint, where

each electrode adjoins the roof of the chamber in the body 11, the electrode will be provided with an annular or distance ring 27 and with a lead 28, which is disposed within the body 11. The outer end of the lead being provided with a contact plate 29, which is screwed on to the lead 28 in order to draw the ring 27 tight against its seating.

Preferably, the contact plates 29 are recessed, and as indicated in the drawings, a nut forms a very suitable contact plate.

In order to connect each contact plate with the electrical supply system, a wiper 30 is provided which may have a protuberance to register within the recess in each contact plate 29; the connection of the wiper to the control cap and to the high tension system is such that the control cap can be rotated within the wiper on top of any one of the contact plates without straining the connection between the high tension wire and the wiper.

In the construction shown, the wiper is provided with a threaded portion 34 screwed into the control cap, and a spherical member 35, which is gripped between two contacts 36, 37, held in the tube 38, to which is also connected the high tension wire 39, the contact 36 being fixed while the contact 37 is slidable within the tube, and under-cut as at 40, to permit introduction of the member 35 through a slot or opening in the tube, the contact 37 being held against the spherical member 35 by means of a spring 41 held in compression by an adjustable plug 42.

Referring now to the modifications shown in Figs. 4 to 8, the insulating body is provided intermediately of each contact recess with a recess 43, into which the wiper 30 engages and in such position the port 22 of the valve 20 does not register with any housing, so that none of the electrodes are in use.

In this construction the electrodes 17 are shown as screwed into the body, preferably obliquely, so that the top portion comes near to the outer wall of the insulating body, this latter being bared as indicated at 44, to expose the top of the electrode, a node 45 on the wiper being adapted to fit into the part 44 to form electrical connection with the respective electrode.

A slightly modified construction is also employed with regard to the connection of the wiper to the control handle. In this construction the wiper is fixed by a screw 46 to the insulating body and a lead 47 extends around the top thereof to the fixing element equivalent to the member 34 shown in Fig. 1.

In a modification as shown in Fig. 9, the control cap is of such dimension as to entirely overlap the exposed ends of the electrodes, and is screwed on to the valve spindle 21 and fixed for rotation therewith by a set screw 21^a, and in this construction a ball

contact 48 is employed on the inner wall of the control cap, the connection to the electrical system being made through the spring 49, the seating 50, which latter member preferably also plugs the boring made to receive the ball and spring, and a lead 51 which is disposed within the body of the control cap, which is bored obliquely, as shown, in order to receive it, this lead 51 being connected to the member 34 of the electrical system. In this latter construction there is practically no wire of the electrical circuit exposed.

From the foregoing description it will be observed that the rotation of the control cap governs the position of the wiper 30 and the valve 20, and that these members are particularly connected so that when the opening 22 in the valve registers with a housing 16, the wiper overlies the contact plate connected to the electrode within that housing, so that sparking may occur at the contact points, while at the same time all the other housings are effectively closed and all the other electrodes are cut out of the operative circuit.

The ignition device may be modified by the introduction of washers such as 31, 32, or 33 to render the plug gas-tight and to avoid injury to the insulating body.

By providing the chambers in the insulating body and holding the electrodes well up into the chambers, as already explained, any intermediate support adjacent the metal body may be eliminated, thereby preventing carbon deposits bridging the space between the electrodes and the metal wall of the housings, as would occur if distance pieces were arranged to steady the electrode near the metal body.

I claim:

1. A sparking plug of the type referred to having in combination an insulating body having a series of integrally formed relatively deep chambers, a metal body perforated to form housings in extension of said chambers, an electrode rigidly held in the top of each chamber and depending into the respective housings, so as to form a spark gap at the open end of each housing, a contact on the side of said insulating body for each said electrode, a control cap mounted on the insulating body, a ported valve adapted to cover all said housings and to register with any one of said housings when the plug is in operation, means connecting said valve to said control cap, a wiper, adapted to sweep all of said contacts, depending from said control cap, and means connecting said wiper to an electrical circuit.

2. A sparking plug of the type referred to, having in combination an insulating body having a series of integrally formed relatively deep chambers, a metal body per-

- forated to form housings in extension of said chambers, an electrode rigidly held in the top of each chamber and depending into the respective housings, complementary 5 spark points at the open end of each housing, a contact on the side of said insulating body for each said electrode, a control cap mounted on the insulating body and overlapping the body to cover all the said 10 contacts, a wiper fitted to the inner wall of said control cap and adapted to sweep all of said contacts, a lead disposed in the body of said control cap for connecting said wiper to an electrical circuit, a ported 15 valve adapted to cover all said housings and to register with any one of said housings when the plug is in operation, and means connecting said valve to said control cap.
3. A sparking plug of the type referred 20 to having in combination an insulating body having a series of integrally formed relatively deep chambers, a metal body perforated to form housings in extension of said chambers, each housing having a constricted end, an electrode rigidly held in the top of each chamber and depending through the respective housing and into the constricted end thereof to form an annular spark gap, a contact on the side of 25 said insulating body for each said electrode, a control cap mounted on the insulating body and overlapping the body to cover all the said contacts, a wiper fitted to the inner wall of said control cap and adapted 30 to sweep all of said contacts, a lead disposed in the body of said control cap for connecting said wiper to an electrical circuit, a ported valve adapted to cover all the constricted ends of said housings and to 35 register with any one of the constricted ends when the plug is in operation, and means connecting said valve to said control cap.
4. A sparking plug of the type referred 40 to having in combination an insulating body having a series of integrally formed relatively deep chambers, a flange near the bottom of said insulating body, a metal body comprising an internally threaded cup 45 adapted to receive the flanged end of the insulating body and a solid stem perforated to form housings in extension of said chambers, each housing having a constricted end, a tubular member adapted to engage within 50 said cup and to hold the said insulating body against said stem, an electrode rigidly held in the top of each chamber and depending through the respective housing and into the constricted end thereof to form an annular spark gap, a contact on the side of 55 said insulating body for each said electrode, a control cap mounted on the insulating body, and overlapping the body to cover all the said contacts, a wiper fitted to the inner 60 wall of said control cap and adapted to sweep all of said contacts, a lead disposed in the body of said control cap for connecting said wiper to an electrical circuit, a ported valve adapted to cover all the said 65 constricted ends of said housings and to register with any one of the constricted ends, when the plug is in operation, and means connecting said valve to said control cap.
5. A sparking plug of the type referred 70 to having in combination an insulating body having a series of integrally formed relatively deep chambers, a flange near the bottom of said insulating body, a metal body comprising an internally threaded cup 75 adapted to receive the flanged end of the insulating body and a solid stem perforated to form housings in extension of said chambers, each housing having a constricted end, a tubular member adapted to engage within 80 said cup and to hold the said insulating body against said stem, electrodes screwed into the insulating body and disposed to depend from the top of said chambers through the respective housings and into the constricted ends thereof to form a series 85 of annular spark gaps, a contact on the side of said insulating body for each said electrode, a control cap mounted on the insulating body, and overlapping the body to cover all the said contacts, a wiper fitted to the inner 90 wall of said control cap and adapted to sweep all of said contacts, a lead disposed in the body of said control cap for connecting said wiper to an electrical circuit, a ported valve adapted to cover all the said 95 constricted ends of said housings and to register with any one of the constricted ends, when the plug is in operation, and means connecting said valve to said control cap.
6. A sparking plug of the type referred 100 to having in combination an insulating body having a series of integrally formed relatively deep chambers, a flange near the bottom of said insulating body, a metal body comprising an internally threaded cup 105 adapted to receive the flanged end of the insulating body and a solid stem perforated to form housings in extension of said chambers, each housing having a constricted end, a tubular member adapted to engage within said cup and to hold the said insulating body against said stem, electrodes screwed obliquely into the insulating body so that 110 the top portion comes near to the outer wall of the said insulating body and so as to depend from the top of said chambers through the respective housings and into the constricted ends thereof to form a series of annular spark gaps, the said top portion of each electrode forming a respective contact therefor by the removal of part of the outer 115 wall of the insulating body to expose the 120 said area, a control cap mounted on the in- 125

ulating body, and overlapping the body to cover all the said contacts, a wiper fitted to the inner wall of said control cap and adapted to sweep all of said contacts, a lead disposed in the body of said control cap for connecting said wiper to an electrical circuit, a ported valve adapted to cover all the

10
said constricted ends of said housings and to register with any one of said constricted ends, when the plug is in operation, and means connecting said valve to said control cap.

In testimony whereof, I affix my signature,
FRANCIS LAYTON ELDREDGE,
